UNITED STATES PATENT OFFICE

JOSHUA L. COWEN, OF NEW YORK, N. Y., AND LOUIS CARUSO, OF IRVINGTON, NEW JERSEY, ASSIGNORS TO THE LIONEL CORPORATION, OF NEW YORK, N. Y., A CORPORATION OF NEW YORK

ELECTRICAL TOY

Application filed April 26, 1928. Serial No. 273,025.

The present invention relates to electrical toys and is more particularly directed toward a toy comprising an electric motor and capable of ready assembly and disassembly into forms which it may be used either as a power plant of general utility for driving tools, hoists, accessories, and the like, or as the power plant of a toy electric locomotive.

The present invention contemplates the provision of suitable parts and subassemblies whereby one can readily assemble a toy locomotive or a toy electric power plant out of these parts.

The invention also contemplates so constructing and arranging the parts that they may be readily put together or taken apart with ease without the use of tools other than a screw driver. It has been found that an electrical toy of this nature can be constructed out of accurately made, rugged substantial parts in such a way that the locomotive power plant or the electric power drive can be very quickly assembled. Such power plant or toy locomotive becomes as substantial and strong and has an efficiency and operative characteristics which are equal to or better than similar sized motors designed for factory assembly with tools, riveting machines and the like.

A further object of the invention is to provide a toy locomotive or power plant wherein it is unnecessary for one to fasten any wires to conduct the current to the various parts of the structure. According to the invention the electrical connections are made simultaneous with the putting of the parts together. In this manner the assembly of the locomotive with the running gear and contact mechanism provides all the electrical connections necessary for the operation of the motor. Similarly the assembly with the motor and frame with the driving shaft and supporting base provides all the electrical connections necessary for a power plant. By this arrangement it will be apparent that there is no opportunity for erroneously connecting the parts as is the case when separable wires must be used. Furthermore the device presents a far more pleasing and workman-like appearance.

According to the present invention it is possible for the manufacturer to place on the market a knocked down locomotive and power plant which the purchaser may readily assemble by following directions which accompany the parts. With the present form of construction it will also be possible for the user of the toy train or toy power plant to obtain replacement of worn, lost or damaged parts without the delay and loss of use of the toy incident to returning it to the service station for repair; for, according to the present invention, it is contemplated that the purchaser will be able to readily take apart the locomotive or power plant and insert a new part which can be obtained from the manufacturer or dealer's stock of spare parts.

According to the present invention it is possible to provide complete outfits of parts and units from which the desired toy locomotive or power plant may be assembled. These parts and units are made up in the form of subassemblies and given the desired configuration and constructional features that they are easily fitted together. The pre-constructed units are so made that the component parts thereof are permanently held together, and yet the purpose and function is readily observable by the boy.

The accompanying drawings show, for purposes of illustrating the invention, two of the many possible embodiments in which the present invention may take form, it being understood that the drawings are illustrative of the invention rather than limiting the same.

In these drawings:

Figure 1 is a composite view illustrating a typical set of parts constituting an outfit for building a wide gage toy locomotive or a power plant using the motor of the wide gage locomotive unit, the parts being arranged in this figure substantially as they might be displayed when packed by the manufacturer;

Figure 2 is a perspective view illustrating the first step of placing the controller unit on one of the side plates;

Figure 3 is an elevational view of the side

plate and controller placed in position thereon;

5 Figure 4 is a perspective view of the plate and controller looking at the opposite or inside of the same, and showing the motor armature in position to pass the armature shaft through the bearing;

10 Figure 5 is a perspective view illustrating the inside of the other frame plate and the motor field and field winding unit, showing these parts in position to be brought together to mount the motor field on this frame plate;

15 Figure 6 is a perspective view of the second plate and field structure assembled;

20 Figure 7 is a perspective view of the first plate, the controller and armature assembled, these two figures, 6 and 7, being placed opposite one another to indicate the manner in which the assembly of the motor unit is completed;

30 Figure 9 is a view similar to Figure 8 showing the reduction gears in place;

35 Figure 10 is a perspective view of the assembled motor and reduction gears;

40 Figure 11 is a perspective view of the contact carrying cross plate or shoe, this figure being placed above Figure 10 to illustrate the manner of assembling these two parts;

45 Figure 12 is a top plan view of the contact shoe carrying member;

50 Figure 13 is a section taken on the line 13—13 of Figure 12;

55 Figure 14 is a side elevational view of the completed toy locomotive;

60 Figure 15 is a perspective view of a completed toy power plant utilizing the motor frame shown in Figure 10 and utilizing the supporting base and power drive parts adapted to complete a toy power plant;

65 Figure 16 is a perspective view of a modified form of toy locomotive power plant more particularly made up for narrow gage toy trains, the gear cover plate and armature shaft bearing member being removed, and parts broken away to show interior construction;

70 Figure 17 is a perspective view of the toy locomotive shown in Figure 16 taken from the opposite side;

75 Figure 18 is a perspective view showing the electrical toy assembled in the form of a power plant utilizing the form of motor shown in Figure 16;

80 Figure 19 is an end view of the power plant shown in Figure 18;

85 Figure 20 is a side elevational view of the toy locomotive of Figures 16 and 17, parts broken away to show interior construction;

90 Figure 21 is an elevational view of the reversing switch and brush rigging unit tak-

en from the opposite direction from which it appears in Figure 17; and

Figure 22 is a section on the line 22—22 of Figure 21.

In the present form of construction as shown in detail in the drawings the outfit from which one can assemble either a toy locomotive or a toy power plant is shown as consisting of a number of distinct parts. These parts may be generally described as including the following. A side plate A, a combined controller and brush rigging assembly B, a motor armature unit C, a second side plate D, a motor field assembly E, a pair of reduction gears F, F, a gear cover plate G, a pair of locomotive trucks H, H having driving wheels and axles, a bottom plate I, provided with contact rollers, a first speed reduction power shaft and assembly J, a second speed reduction power shaft and assembly K, a power plant base L, and nine screws.

In making up the toy locomotive, the parts J, K and L are not employed, while in making up the toy power plant the parts H and I are not employed.

The side plate A may be a flat smooth steel plate provided with holes, slots and projections such as indicated in the drawing. These special parts will be enumerated as the description proceeds.

The combined controller and brush rigging assembly B which is shown in detail in Figures 1, 2, 4 and 7 includes a rectangular insulating plate 20 which carries all these parts. This insulating plate carries two connecting straps 21 and 22 the former being the lead in connection for the controller as indicated more clearly in Figure 4. The lower end of this strap has an outwardly extending foot 23 for a purpose to be pointed out later. The upper end of the insulating plate 20 carries a reversing switch and controller for the motor. This reversing switch includes a pivotally mounted operating lever 25 which is mounted about a center 26. It carries contacts 27 and 28 indicated in dotted lines in Figure 3. These contacts are cooperative with four posts 29, 30, 31 and 32. The post 29 is connected at the upper end of the lead in strap 21 while the post 30 is connected at the upper end of the brush lead strap 22 and the post 32 is connected to the other brush lead strap 33. The post 31 connects with a contact button 34 fixedly carried by the insulating plate.

The contact strips 22 and 33 each carry a brush rigging as indicated at 35. On making up this brush rigging the lower ends of the straps 22 and 33 are rolled as indicated at 36 to provide a round passageway or holder for a brush 37. Each of these brushes is carried on the end of a spring 38 which urges it inwardly toward the commutator of the motor. Each of the brush riggings is pro-

vided with a brush lifter in the form of a lever 39 pivoted about the screw 40 and having a free end 41 engageable with the spring 38 to lift the brush.

5 The insulating plate 20 and the metal plate A are provided with pairs of aligned holes 42 and 43 to receive screws 42' and 43' for fastening these two parts together. To facilitate aligning these two parts, the insulating plate 20 carries pins 44 which pass into holes 44' in the metal plate and the metal plate carries a bushing 45 for the armature shaft, which bushing passes through a hole 45' in the insulating plate. The plate A is also provided with cut-outs as indicated at 46 and 47 which accommodate the prongs 48 used in fastening the conducting strips on the insulating plate 20. The slot or cut out 46 also permits passing the controller handle 20 through the slot as indicated in Figure 2.

The assembly of these two parts is accomplished as indicated in Figure 2 in a very simple manner, it being merely necessary to pass the handle of the controller through 25 the slot, and swinging the parts into position so that the pins 44 pass through the holes 44' and the bushing 45 passes through the hole 45'. The screws 42' and 43' may then be inserted in place and this part of the assembly 30 is completed, as shown in Figures 3 and 4.

The commutator assembly C may, as here shown, include an armature shaft 50, armature field structure 51, armature windings 52, spur driving gear 53 and commutator 54. These parts are provided as an assembled unit and may be inserted into the motor assembly as indicated in Figure 4. To accompany this operation it is merely necessary to 40 press the tips 39 of the brush lifting fingers toward one another and pass the shaft 50 through the bushing 45. This brings the parts to the assembled condition as illustrated in Figure 7.

45 The plate D resembles in general the plate A but it is intended for carrying the field structure E. As appears in Figures 1 and 5 the plate D is provided with four small holes 60, and with two short spacers 61 riveted to it and provided with tapped holes 62.

The motor field assembly E is made up to have the usual laminated field structure 63 and field windings 64. This field structure is held together by rivets indicated at 65 and 55 having reduced end portions 66 cooperative with the holes 60 in the frame plate D. The field structure is also provided with screw receiving holes 67 through which screws 68 may be passed to thread them into the tapped holes 62 in the bosses 61 carried by the frame plate. In this manner the field structure and plate may be brought together to place the parts in position as shown in Figure 6.

60 One end of the field winding is grounded by soldering it to a rivet, as indicated at 64'.

The other end 64'' is connected to a strap 70 fixedly mounted in the insulating spool ends 64a and 64b. The strap 70 carries a spring 70 pressed plunger 69 which projects outwardly as indicated in Figure 6. It is then in a position to come opposite the contact 34 carried on the controller assembly.

The plate D as here shown also carries three spacers or posts 71, 72 and 73 preferably riveted to it and provided with reduced end portions cooperative with holes 74, 75, and 76 in the plate A. The parts shown in Figures 6 and 7 may be brought together by merely moving them toward one another in the positions there indicated so as to bring the reduced ends of these spacers through the corresponding holes after which screws 77 may be passed into the threaded holes 71', 72' and 73' in the spacers to clamp the plates and supporting parts together. When the parts have been assembled to this extent the armature shaft 50 and pinion 53 project out through a hole 78 in the frame plate D.

The outside of the frame plate D is provided with two posts 79 shown in Figure 8, 90 adapted to receive the reducing gears F which may be assembled so that the parts will appear as shown in Figure 9. These two gears are each in mesh with the pinion 53. The plate D is also provided with two posts 95 or lugs 80 having reduced end portions and threaded holes. The cover plate G above referred to is adapted to fit over the parts as indicated in Figure 10. This cover plate has small holes 81 to receive the studs 79, has a bearing hole 82 for the armature shaft 50 and is provided with two holes to permit passing screws 83 into the supporting studs 80. All the foregoing parts may be assembled in the manner indicated, and the device 100 in this stage of assembly is in condition for further assembly to make it into a toy locomotive power plant or a toy unit for general purposes.

105 Assuming that it is to be assembled into a toy locomotive power plant, the operations will be described. During these operations one employs the two truck units H and the current collector or bottom plate I. As shown in Figure 1 these truck units each have a shaft 89 fixedly carrying a driving gear 90 and a pair of track wheels 91. The shafts 89 also loosely carry bushings 92 having undercut portions 93 as indicated. The bushings are held in place by prick marks 89'.

110 The frame plates A and D are provided with slots 94, 95, 96 and 97. These slots are arranged to be opposite one another in pairs when the frame plates and motor parts are assembled as shown in Figure 10. These 115 slots provide guide ways to receive the bearing members 92, and the next step in assembling the locomotive power plant is to place these two axles and associated parts in position by merely sliding the bushings down the 120 125

slots thereby bringing the gears 90 into mesh with the reducing gears F.

The current collector plate or bottom plate I as shown in Figures 1, 11, 12 and 18, is adapted to be fastened in place after the running gear has been installed.

This bottom plate and contact carrier consist essentially of a sheet metal stamping 100 which fits the motor frame, and a pair 10 of rail contacting rollers 101 and 102 insulatively supported from the stamping 100 and adapted to ride on the third rail of the toy railroad track on which the locomotive is to be used. To insulatively support the rollers 15 a strip of insulating material 103 is secured to the stamping 100. As here shown the method of securing these parts together includes a plurality of prongs 104 bent over onto the strip of insulation and a pair of 20 apertured prongs 105 adapted to receive the reduced end portions 106 of the insulating strip. This insulating strip carries a flexible metal strip 107 on the ends of which are mounted saddle pieces 108 which extend down 25 through holes 109 in the stamping 100 so as to carry the rollers 101 and 102 spaced below the body of the stamping 100. The resilient roller supporting strip 107 is held in place on the insulating strip 103 by a stamping 110 30 and prongs 111, which are folded over the metal strip 107 and underneath the insulating strip 103, the stamping 100 being cut away as indicated at 112 in section in Figure 13 to keep the prongs 111 out of contact with 35 the stamping. The contact carrier 107 is prevented from twisting out of place by the roller supporting saddles 108 which pass down alongside the fixedly carried insulating strip 103. The stamping 110 carries a spring 40 pressed plunger 113 for a purpose to be described.

The stamping 100 is shaped so as to securely fit the motor parts heretofore assembled and is arranged that it cannot be improperly placed in position on the same. The stamping has upwardly bent end members 114 and 115 slotted as indicated at 116 and 45 adapted to pass outside the posts 71 and 72. The sides of the stamping 100 are provided 50 with four upwardly extending projections 117 adapted to fit outside the frame plates A and B and to engage with the bushings 92 on the shafts of the running gear. The plate A is provided with projections 118 adapted 55 to pass through slots 119 in the stamping 100 thereby preventing assembling these parts improperly.

To complete the assembly of the locomotive motor the bottom plate 100 and parts 60 carried thereby is inserted in place, which may be accomplished by merely lowering it from the position shown in Figure 11 onto the structure as indicated in Figure 10. This permits the slots 116 to pass by the shanks of 65 thumb screws 120 carried by the spacers 71

and 72. At the same time the projections 117 are brought against the bushings on the wheel axle shafts and when the thumb screws are tightened this bottom stamping and contact carrier is secured in position.

During this operation the spring pressed plunger 113 is brought against the outstanding foot 23 on the controller brush rigging unit B. The relative position of these parts at that time are indicated in Figure 1. When the parts have been assembled as has been described, the complete power plant for the toy locomotive will have been assembled utilizing the parts designated as A, B, C, D, E, F, G, H, I and the nine screws provided in the outfit. It will be noted that it is unnecessary to connect or disconnect any wires whatever in assembling the motor. All electrical parts are securely carried by various subassemblies and when they are put together, all necessary connections are made.

The path of current through the motor may be described as follows: From the contact rollers 101 and 102 through the yielding spring supporting strap 107 to the stamping 110 thence through the spring pressed plunger 113 to the foot 23 of the strap 21, then through the reversing switch or controller and brush rigging and through the motor armature where the current is carried to the contact button 34 on the controller unit. This current will continue through the field winding to the field structure and thence to the motor frame. The extent of movement of the reversing switch 25 is limited by two stops 118 on the plate A.

In order to facilitate assembly of the motor, the two screws 42' and 43' used for fastening the controller brush assembly onto the plate A, the three screws 77 used for fastening the plate A onto the spacers 71, 72 and 73, and the two screws 83 used for fastening the plate G in position are all the same size and length. The two screws 68 used for fastening the field assembly onto the plate D 105 are longer but may be made to have the same thread.

When it is desired to assemble the outfit into the form of a toy electric power plant for operating various forms of toys, the parts are as above described assembled to bring them to the state or condition shown in Figure 10. Instead of using the units H and I to make up a toy locomotive one uses the units J, K and L to make up a toy power plant.

The unit J has a shaft 130 similar to the shaft 89, and is provided with a gear 131 like the gear 90 and with bushings 132 like the bushings 92. The shaft J also carries at one end a comparatively large pulley 133 and at the other end a small pulley 134 and a pinion 135.

The unit K has a shaft 136 which carries a large gear 137, a drum 138 and a sprocket 130

wheel 139. In assembling these parts the unit K is first inserted in place by passing the shaft portion 136 through the holes 140 and 141 in the plates A and D. To make improper assembly impossible, these holes are 5 larger than other holes in the side plates, and may be the only holes opposite one another. The unit J is lowered along the slots in the same manner that the units H were inserted bringing the gear 131 in mesh with the reduction gear unit F and bring the pinion 135 into mesh with the gear 137 on the unit K. As this gear 137 comes in behind the pulley 134 the unit K is securely held in 10 position so that it cannot slide out of its bearings.

The base plate unit L is then inserted in place. This unit as shown in Figures 1 and 15 is in the form of an inverted channel shaped stamping 150 adapted to support the power plant on a flat surface. This stamping 150 has upwardly bent side lugs 151 corresponding with the lugs 117 carried by the unit I and adapted to pass outside the frame 20 plates A and D as indicated in Figure 15. One pair of these lugs will secure the unit K in position, the other pair merely passing up outside the motor frame to facilitate aligning the motor parts. The stamping 150 is 25 also provided with two lugs 152 similar to the upwardly bent ends 114 and 115 so that the unit L may be fastened onto the spacers 71 and 72 by the thumb screws 120 as indicated in Figure 15. The stamping 150 also 30 carries an upwardly and inwardly extending shelf 153 adapted to pass inwardly between the lugs 118 on the plate A. The end 154 of the stamping carries a pair of binding posts 155 and 156 one of which is insulatively 35 supported from the face plate. This insulated binding post 156 is connected by means of a conducting strip 157 with a plunger member 158 similar to the plunger member 113. The plunger member 158 is carried by the 40 shelf 153 and the contact strip 157 is covered over and supported by an insulating strip 159.

When the units J, K and L are assembled as have been described, the electrical connections for the motor have been simultaneously completed. The current can pass from the binding post 156 through the strap 157 and plunger 158 to the foot 23 carried by the controller unit B and thence through the motor 45 which has been described.

When the unit has been assembled for power plant purposes it will be apparent that one has available a high speed pulley 132, a low speed pulley 134, and a still lower speed wind- 50 ing drum 138 and sprocket wheel 139.

Figures 16 to 21 illustrate a toy electric locomotive and power plant with the parts of convenient size for building up a toy locomotive for use on narrow gage toy railroad track. This outfit is made up and assembled 55

in a manner generally similar to that employed for the larger wide gage outfit. The outfit going to make up the toy locomotive and power plant as shown in Figures 16 to 20, inclusive, consists of a number of separable units having the same general characteristics as the units shown in Figure 1 and capable of readily being assembled to produce a toy locomotive or power plant. These separate units, however, are, except for the trucks 70 and power shafts, of different detailed design although in general are for the same purpose.

The narrow gage outfit includes a side plate A', a combined reversing switch and brush rigging unit B', an armature unit C', a second side plate D', a field unit E', reduction gears F', a gear cover plate G', locomotive trucks H', a contact carrying bottom plate I', power shafts J' and K', a power plant base unit L', and ten screws.

The toy locomotive of Figures 16, 17, 20, 21 and 22 is assembled in a slightly different order than that above outlined with respect to the form shown in Figure 1. The motor field unit E' is first mounted on the plate D'. This mounting is accomplished by means of screws 200 which pass through holes in the field structure and which are threaded into spacers 201 carried by the plate D'. The plate A' is then placed in position. This plate A' carries four spacers 202, 203, 204, 205 similar to the spacers 71, 72 and 73 having reduced ends which fit into the corresponding holes in the plate D. Screws 206 are threaded to 100 the spacers to fasten the two plates together. The reduction gears F' will then be passed onto the supporting posts 207 as indicated in Figure 16, after which the plate G' may be fastened in place by the screws 208 threaded into the posts 209 carried by the plate. The plate G' has wings as indicated at 210 which overlie the reduction gears F' and hold them in place on the studs 207. The armature shaft unit C' may then be passed through 105 a large hole 211 in the plate A' so as to bring the end 212 of the armature shaft into the bushing 213 carried by the side plate G'. This will at the same time bring the driving pinion 214 on the armature shaft into mesh with the reduction gears F'.

The brush rigging controller unit B' is then mounted in place on the studs 215 and 126 carried by the plate A' provided for this purpose. The stud 215 has a reduced outer end adapted to pass through the bushing 217 carried by the unit D' while the stud 216 passes through the hole 218 in the insulating plate 219 of the unit B'. This unit also carries a metallic bushing 220 to receive the armature shaft 212. The 110 unit B is held in place by screws 221 threaded into the studs 215 and 126. The locomotive truck units H' are next mounted in place by passing the bushings 222 similar to the bushing 132 upwardly through the slots 223 in 115 120 125 130

the side plates A' and D'. This running gear is held in place by a transverse bottom plate I' which is secured in place by thumb screws 224 threaded into the spacers 203.

5 The field unit E' is made up to have the usual laminated field structure 230 and field winding 231. It also carries two sheets of insulation 232 and 233 between which the coil 231 is wound. These insulating members 10 are designed so as to fit into the large slots or openings 234 and the small slots or openings 235 in the plates A' and D'. A current conductor 236 indicated in dotted lines in Figure 20 carries, at its lower end a plunger 237 15 cooperative with the lead in conductor 227. This conductor 236 is connected to one side of the field winding. The other side of the field winding is connected to a metal strip 238 carried in the upper front side of the field 20 structure as indicated in Figure 20. This conductor strip 238 carries a forwardly extending plunger 239 adapted to pass through a hole 240 in the front plate A'. The laminated field is held together by rivets in the usual 25 manner. The heads of these rivets passing out through small alignment holes 241 in the plate D'.

The armature unit C' is of more or less conventional construction having the usual 30 shaft 212, pinion 214, armature field 215, windings 216, and commutator 217.

A brush rigging controller unit B' as shown in Figures 17, 21 and 22, comprises as 35 has been described, an insulating sheet or plate 219 on which all of these parts are mounted. This unit also includes a current supply terminal 245 adapted to engage the plunger 239 when the parts are assembled into position. The plate B' also carries an 40 oscillatory reversing switch element 246 similar to the reversing switch 25 heretofore described in detail. The fixed contacts 247 and 247' of the reversing switch are each connected to brush rigging 248. The other fixed 45 contact of the reversing switch is indicated at 249. It is connected by a strap 250 with the bushing 217 through which the stud passes, thereby grounding the circuit.

The form of brush rigging here shown, is 50 made up out of a simple sheet metal stamping. The insulating plate 219 is provided with two openings 251 and 252 having circular ends 253 and narrow slots 254. The brush rigging stampings have cylindrical 55 portions 255 adapted to pass through the enlarged ends of the slots, and also prongs 256 and 257 which pass through the narrow portion 254 of the slots. These prongs are bent over into the insulating plate as indicated in 60 Figure 17. The stamping also has two parallel portions 258 and 259 which extend from the holes 253 back to the conductor plates 260 which are connected to the posts 247 and 247'. The ends of these brush rigging stampings 65 have outwardly bent feet 261 which overlie

the conductor plates 260 and which are held in close contact to the same when the prongs 256 and 257 are bent over against the outside of the insulating plate. The brush 263 is carried in the cylindrical part of the brush 70 holder. This brush is carried on the end of a spring 264 which is coiled about an anchor screw 265. The end of a spring 266 is passed under an inwardly bent prong 267 on the brush rigging stamping. The spring is also 75 held in behind a bent over ear 268 which prevents the spring moving the brush out of the holder. The prong 256 may, if desired, be provided with posts 269 adapted to receive 80 clips to connect in head lights so that the headlights are lighted in accordance with the direction of travel of the locomotive.

The plate L' shown in Figures 18 and 19 is in general similar to the base plate L shown in Figure 1. It is provided with upwardly 85 extending prongs 270 adapted to overlie the slots 223 in the socket plates A' and D' and hold in place the shaft J'. It is also provided with binding posts 271, one of which is connected to a contact post 272 cooperative 90 with the terminal 237. The base plate L' is provided with an apertured inwardly extending flange 275 to receive the aligning lug 229.

The motor construction shown in Figures 95 1-15 inclusive forms the subject matter of divisional application Serial No. 513,071 filed February 3, 1931.

It is obvious that the invention may be embodied in many forms and constructions, and we wish it to be understood that the particular forms shown are but a few of the many forms. Various modifications and changes being possible, we do not limit ourselves in any way with respect thereto. 105

We claim:

1. A toy locomotive comprising two side plates detachably fastened together in spaced relation, a motor field, motor armature, and brush rigging detachably supported by the 110 plates in operative relation and provided with current connections completed by the assembly of said parts for motor operations, the plates having pairs of aligned slots extending upwardly from the lower edges 115 thereof, a pair of locomotive truck units each including an axle shaft, a driving gear and track wheels, the units being slidable into the aligned slots to dispose the wheels outside the plates, reduction gearing connecting the armature and gears on the truck units, and a detachably mounted base plate unit having flanges which overlie the slots to hold the truck units in place, and carrying insulated 120 collector contacts for cooperation with a third rail between the track wheels. 125

2. A toy locomotive comprising two side plates detachably fastened together in spaced relation, a motor field, motor armature, and brush rigging detachably supported by the 130

- plates in operative relation and provided with current connections completed by the assembly of said parts for motor operation, the plates having pairs of aligned slots extending upwardly from the lower edges thereof, a pair of locomotive truck units each including an axle shaft, a driving gear and track wheels, the units being slideable into the aligned slots to dispose the wheels outside the plates, reduction gearing connecting the armature and gears on the truck units, and a detachably mounted base plate unit having flanges which overlie the slots to hold the truck units in place, and carrying insulated collector contacts for cooperation with a third rail between the track wheels, said base plate unit also carrying a current supply terminal cooperative with one of the aforesaid current connections.
20. 3. A toy outfit comprising separable units capable of being fastened together to form a toy electric locomotive or a toy electric power plant, said units including side plates, a motor field unit, a motor armature unit, and a control switch and brush rigging unit detachably fastened together to form a motor body, the side plates having pairs of aligned slots extending upwardly from the lower edge thereof, one of the plates detachably carrying a pair of reduction gears meshing with a pinion on the armature shaft, said units also including a pair of truck units having track wheels and driving gears mounted on an axle shaft, and a driver unit also mounted on an axle shaft and having a driving gear, the truck units and driver unit each being capable of being optionally placed in the slots to bring the gears therein in mesh with one of the reduction gears, and bottom plate units fitting the two side plates and having provisions for holding the shafts in the slots, one of said units having a base adapted to support the power plant when the driver is in place, while the other bottom plate unit carries contact rollers engageable with a third rail of a toy railroad.
4. A toy outfit comprising separable units capable of being fastened together to form a toy electric locomotive or a toy electric power plant, said units including side plates, a motor field unit, a motor armature unit, and a control switch and brush rigging unit detachably fastened together to form a motor body, the side plates having pairs of aligned slots extending upwardly from the lower edge thereof, one of the plates detachably carrying a pair of reduction gears meshing with a pinion on the armature shaft, said units also including a pair of truck units having track wheels and driving gears mounted on an axle shaft, and a driver unit also mounted on an axle shaft and having a driving gear, the truck units and driver unit each being capable of being optionally placed in the slots to bring the gears therein in mesh with one of the reduction gears, and bottom plate units fitting the two side plates and having provisions for holding the shafts in the slots, one of said units having a base adapted to support the power plant when the driver is in place, while the other bottom plate unit carries contact rollers engageable with a third rail of a toy railroad.
5. A toy outfit comprising separable units capable of being fastened together to form a toy electric locomotive or a toy electric power plant, said units including side plates, a motor field unit, a motor armature unit, and a control switch and brush rigging unit detachably fastened together to form a motor body, the side plates having pairs of aligned slots extending upwardly from the lower edge thereof, one of the plates detachably carrying a pair of reduction gears meshing with a pinion on the armature shaft, said units also including a pair of truck units having track wheels and driving gears mounted on an axle shaft, and a driver unit also mounted on an axle shaft and having a driving gear, the truck units and driver unit each being capable of being optionally placed in the slots to bring the gears therein in mesh with one of the reduction gears, and bottom plate units fitting the two side plates and having provisions for holding the shafts in the slots, one of said units having a base adapted to support the power plant when the driver is in place, while the other bottom plate unit carries contact rollers engageable with a third rail of a toy railroad, these units carrying insulatively supported conductors placed into current conducting relation for completing the motor circuits upon assembly of the units.
6. A toy outfit comprising separable units capable of being fastened together to form a toy electric locomotive or a toy electric power plant, said units including side plates, a motor field unit, a motor armature unit, and a control switch and brush rigging unit detachably fastened together to form a motor body, the side plates having pairs of aligned slots extending upwardly from the lower edge thereof, one of the plates detachably carrying a pair of reduction gears meshing with a pinion on the armature shaft, said units also including a pair of truck units having track wheels and driving gears mounted on an axle shaft, and a driver unit also mounted on an axle shaft and having a driving gear, the truck units and driver unit each being capable of being optionally placed in the slots to bring the gears therein in mesh with one of the reduction gears, and bottom plate units fitting the two side plates and having provisions for holding the shafts in the slots, one of said units having a base adapted to support the power plant when the driver is in place, while the other bottom plate unit carries contact rollers engageable with a third rail of a toy railroad, each of said units having such size and configuration that assembly of the parts in but one fashion is possible.
7. A set of toy parts comprising an electric motor field unit, a motor armature unit, supporting plates for the field and armature units, means for detachably fastening the plates and units together, a plurality of interchangeable power driving devices each having shafts slideable into position determined by the configuration of the plates to be in driving relation to the armature unit, and a plurality of plate-like members of different forms, each capable of being detachably fastened to the supporting plates after the power driving devices have been placed in position and when so fastened in place immovably securing the power driving devices in position.
8. A set of toy parts comprising an electric motor field unit, a motor armature unit, a brush rigging unit, supporting plates for the field and armature units, means for detachably fastening the plates and units together, a plurality of interchangeable power driving devices each having shafts slideable into position determined by the configuration of the

plates to be in driving relation to the armature unit, and a plurality of plate-like members of different forms, each capable of being detachably fastened to the supporting plates after the power driving devices have been placed in position and when so fastened in place immovably securing the power driving devices in position, said units and the plate-like members permanently carrying connectors associable together to complete the motor circuit upon the assembly of the parts.

8. A set of toy parts comprising an electric motor field unit, a motor armature unit, supporting plates for the field and armature units, means for detachably fastening the plates and units together, a plurality of interchangeable power driving devices each having shafts slideable into position determined by the configuration of the plates to be in driving relation to the armature unit, and a plurality of plate-like members of different forms, each capable of being detachably fastened to the supporting plates after the power driving devices have been placed in position and when so fastened in place immovably securing the power driving devices in position, one of said plate-like members carrying current collecting rollers adapted to supply current to the motor.

9. A set of toy parts comprising an electric motor field unit, a motor armature unit, a brush rigging unit, supporting plates for the field and armature units, means for detachably fastening the plates and units together, a plurality of interchangeable power driving devices each having shafts slideable into position determined by the configuration of the plates to be in driving relation to the armature unit, and a plurality of plate-like members of different forms, each capable of being detachably fastened to the supporting plates after the power driving devices have been placed in position and when so fastened in place immovably securing the power driving devices in position, said parts having interfitting elements non-symmetrically arranged to require assembly in a predetermined manner only.

10. A set of toy parts comprising an electric motor field unit, a motor armature unit, a reversing switch and brush rigging unit, supporting plates for the field and armature units, means for detachably fastening the plates and units together, a plurality of interchangeable power driving devices each having shafts slideable into position determined by the configuration of the plates to be in driving relation to the armature unit, certain of said devices being in the form of locomotive trucks having wheels, and a plurality of plate-like members of different forms, each capable of being detachably fastened to the supporting plates after the power driving devices have been placed in

position and when so fastened in place immovably securing the power driving devices in position, one of said plate-like member having current collecting rollers adapted to contact with a third rail between the wheels for supplying current to the motor, said unit and plate-like members permanently carrying connectors associable together to complete the motor circuit upon assembly of the parts.

Signed at Irvington, in the county of Essex and State of New Jersey, this 19th day of April, 1928.

JOSHUA L. COWEN.
LOUIS CARUSO.
